(57) **CLAIM**

The ornamental design for a ball cap, as shown and described.

DESCRIPTION

FIG. 1 is a rear perspective view of the ball cap in accordance with my invention;

FIG. 2 is a rear elevation view thereof;

FIG. 3 is a front elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines shown in the drawings illustrate portions of the ball cap that form no part of the claimed design.
